UNITED STATES PATENT OFFICE.

LEOPOLD HAUSER, OF NEW YORK, N. Y.

BAG.

1,283,170.

Specification of Letters Patent.

Patented Oct. 29, 1918.

Application filed December 13, 1915. Serial No. 66,502.

To all whom it may concern:

Be it known that I, LEOPOLD HAUSER, a citizen of the United States, and a resident of the borough of Manhattan, city of New York, county of New York, and State of New York, have invented certain new and useful Improvements in Bags, of which the following is a specification.

The invention relates to bags such as are applicable for use as receptacles for handkerchiefs, collars, cuffs, ties, jewelry or the like and the object of the invention is to provide a bag which will have a plurality of compartments that will be separated from each other and which bag will occupy a comparatively small space when one or both of the compartments is or are not utilized.

The invention particularly relates to a bag having an upper compartment which is suitable for holding such articles as collars, cuffs or the like and a lower box-like receptacle or drawer suitable for handkerchiefs, jewels or other articles, which receptacle is capable of being removed by lateral movement.

The invention furthermore relates to a bag having a circular hollow receiving portion in the upper part thereof and a circular base or lower part in which there is a lateral sliding drawer or receptacle having parallel sides and an exposed end which conforms with the outer curvature of the bag. The upper and lower portions of this bag are separated by a transverse partition which is secured to the lining of the bag.

The invention furthermore relates to a bag having a drawer which is provided with a small pull, the casing therefor having a drawer securing strap located so that it will cover the drawer pull when holding the drawer in closed position. The invention also relates to other improvements which will be pointed out more specifically herein-after.

As showing certain specific embodiments of the invention reference is made to the drawings forming a part of this specification in which drawings,

Figure 1 is a side view partially in section of one form of bag showing the drawer of the latter in open or extended position.

Fig. 2 is a plan view partially in section of the bag shown in Fig. 1.

Fig. 3 is a side view of the bag shown in Fig. 1 with all the parts in closed position.

Fig. 4 is a partially inverted view of the bottom of the bag showing the manner in which the same is cut away or recessed to form a receiving portion for the end of the drawer securing strap.

Fig. 5 is a partially-vertical sectional view taken through a base portion of the bag.

Fig. 6 is a side elevation partially broken away of another form of bag embodying the invention.

Fig. 7 is a plan view partially broken away of the bag shown in Fig. 6.

The bag shown in Figs. 1 to 5 is designated by the reference character 1 and comprises an upper hollow receiving portion 2 that is suitable for holding such articles as collars, cuffs and the like and a lower or base compartment 3 having a drawer 4 therein which is suitable for receiving such articles as jewelry, handkerchiefs, ties, veils and the like. The upper and lower compartments are separated by a relatively stiff intermediate partition 5. The base 6 comprises a relatively stiff member 7 and a padded portion 8. Extending between the intermediate partition and the base 6 are arc-shaped members 9 and 10 and parallel drawer guiding members 11 and 12. All of these are vertically extending members and they are comparatively stiff and are rigidly connected with the intermediate partition and the base thereby forming a firm and strong lower compartment or casing for receiving the drawer 4. The outer covering or outer member 13 of the body of the bag is preferably made of leather and extends the full length thereof and is cut out where the drawer enters the base and where it is thus cut it is turned inwardly to the underside of the intermediate partition 5, to the vertical members 11 and 12 and to the upper part of the base 6. The lower end of said outer cover 13 is turned under and secured to the relatively stiff or rigid portion 7 of the base and is subsequently covered by the padded portion 8 of the base so that the bag will present a finished appearance.

The drawer may be sub-divided into smaller sections as into the parts 14, 15, 16, 16¹, 17 and 17¹ which may be utilized for such articles as may be desired to be placed therein. The drawer is also provided with a small pull 18 and there is also secured to the outside of the case or cover a drawer securing strap 19 the free end of which may

be secured to the base 6 by means of a securing clip 20 which extends between the base and strap. The base is recessed or cut away as at 21 to receive this end of the strap 5 and this recess is of sufficient depth so that the securing clip will not project materially below the bottom of the bag.

In the construction shown in Figs. 1 to 5 the lower end of the securing clip is substantially flush with the lower side of the base portion. The cover 13 instead of being made of leather may be made of any other suitable material and it is also provided with a lining 13' that is secured to the upper end of the outer body member in any suitable and well known manner. The lower end of this lining is secured to the transverse partition in any suitable manner. The transverse partition preferably comprises two relatively stiff members 5¹ and 5² which may be of material such as pasteboard. The exposed surfaces of the members 5¹ and 5² are covered with a layer of fabric or other lining material indicated by 5^a and 5^b. The edges *a* and *b* of the lining 5^a, 5^b extend into the spaces between the relatively stiff partition members 5¹ and 5² and said edges are respectively secured to said members as by means of glue. Portions 30 of the inner lining 13¹ extend into the space between the relatively stiff partition members 5¹ and 5² and these portions of the body lining are secured as by means of glue to the members of the transverse partition between which they extend. The upper end of the bag is closed in any suitable manner as by means of a draw-string 22 which passes through eyelets 23.

The general construction of the bag shown in Figs. 6 and 7 is substantially the same as that shown in Figs. 1 to 5. The drawer or box-like receptacle of the bag shown in Figs. 6 and 7 has been shown with only one large center compartment 14¹ and end 45 compartments 17 and 17¹. It has also been shown as deeper than the box shown in Figs. 1 to 5. The upper part of the bag instead of being provided with a draw-string, such as is shown in Fig. 1, is closed by means 50 of a swinging cover 24 which has a hinged connection as at 25. This cover is substantially flat and is made in any suitable manner as for instance by means of a relatively stiff pasteboard that is covered on the exterior with the same material as the outer covering of the bag and it is preferably lined with the same material as that with which the bag is lined. The outer covering of the bag is designated by the reference character 60 26 and extends the full height of the bag. The lining 27 is secured to the transverse partition 5 and to the upper portion of the cover in any suitable manner. The top of the body is reinforced by a metallic ring 28 65 which is substantially circular and which

conforms to the shape of the cover. This ring reinforces the upper portion of the bag. The cover and ring can be moved toward the lower compartment of the bag since the body and lining are made of flexible material and can be crushed.

From an inspection of Fig. 5 it will be observed that the outer covering passes over the reinforced ring and is folded back upon itself and that the lining is folded over and the parts thus folded are secured together by the stitching at 29. The bag shown in Figs. 6 and 7, except as above enumerated, is substantially the same as the bag shown in Figs. 1 to 5.

It will be manifest that the invention may be combined in various forms and modifications without departing from the spirit and scope of the invention.

What I claim is:

1. A bag of the class described having a flexible outer body member, a lining secured to said body member, a transverse partition secured intermediate the ends of the body member to said lining, said body member being reinforced at one end by means of a ring, and a hinged cover secured to the end thus reinforced.

2. A bag which is provided with a plurality of compartments and having an outer body member, a lining for said body member, a transverse partition which extends between said compartments, said transverse partition comprising a plurality of relatively stiff members between which the lining extends and to which the lining is secured.

3. A bag of the class described having a flexible outer body member, a transverse partition and a hinged cover on one end thereof, the flexible body having a lining which is secured thereto at or adjacent to one end thereof, the transverse partition comprising a plurality of comparatively stiff members the exposed sides of which are covered with a suitable material that extends into the space between said members and which is secured to the members that it covers, the lining also extending into the space between said relatively stiff members and being secured to them, at least one end of the body being provided with a reinforcing ring that serves to maintain the flexible free edge of the body in proper shape, said cover being hinged to the end thus reinforced, the bag also being provided with means for detachably securing the cover in closed position.

4. A bag of the class described having a body, a transverse partition secured to and located intermediate the ends thereof so as to provide a compartment on each side of the partition, said body having an end reinforced by a ring and there being located at the end thus reinforced a cover which can

be detachably secured in closed position, the body being flexible between the transverse partition and the end thus reinforced.

5. A bag of the class described comprising a flexible body having a lining and a reinforcing ring at one end thereof, said bag having a transverse partition secured to the lining intermediate the ends of the body and a cover secured to the body at the end 10 thus reinforced, which cover conforms in shape to the reinforcing ring which is provided in the body, the bag also being provided with means for detachably securing the cover in closed position.
- 15 6. A bag of the class described having an outer cover extending the full height of the bag, an intermediate partition extending horizontally forming between it and the bottom of the bag a lower or base compartment, 20 vertical partitions between the intermediate partition and the bottom, the cover being slit and turned into the space formed by the base and partitions to provide an opening for a drawer, and a drawer in the base compartment which can be operated by lateral 25 movement.

7. A bag having an opening at the side, a receptacle that enters the opening the front of which receptacle is flush with the face of the case when in closed position, said receptacle being normally retained in place by means of a strap an end of which strap rests in an opening made in the bottom, the depth of the opening in the bottom being sufficient so that a securing clip which is between the 30 strap and the bottom will not project beyond the lowest face of the bottom.

8. A bag having an opening, a drawer entering the opening, a pull on the end of the drawer, and a drawer securing strap, on 35 the case of the bag, which strap runs across the face of the drawer and over the pull thereof whereby the pull is concealed when the strap is holding the drawer in place.

This specification signed and witnessed 40
this 11th day of December 1915.
